WEFT FEELER FOR AUTOMATIC LOOMS FOR WEAVING

Application filed January 30, 1931, Serial No. 512,457, and in France September 24, 1930.

The present invention relates to improvements in weft feelers for automatic looms for weaving employing directly the yarn on cardboard or paper tubes to cause the changing of the shuttle when the tube becomes exhausted.

The invention comprises a bracket affixed to the loom frame, an arm mounted on the bracket to slide normally to the shuttle to directly engage the weft on the shuttle tube and a spring controlled lever pivoted in a slot in the bracket normally engaging both the shuttle side and a stop on the sliding arm but which when the sliding arm moves owing to a shortage of weft on the tube releases the shuttle changing mechanism.

It will be described with reference to the accompanying drawing which is given by way of example.

Fig. 1 is a front elevation showing the position with the shuttle in operation when the tube is carrying sufficient yarn.

Fig. 2 is a vertical section through the feeler on a line 2—2 Fig. 1.

Fig. 3 is a view similar to Fig. 1 at the moment of knocking off.

Fig. 4 is the corresponding section on line 4—4 Fig. 3.

In the embodiment of the invention here shown, on the frame of the loom is mounted a bracket *a* which is formed with a slot *b* and a socket *c*.

In the slot *b* a lever *d* provided with a pivot pin *e* slides. This lever is drawn towards the shuttle *n* against which it bears by a spring *f*. Said lever is provided near its free end with an abutment *h'* having an oblique edge which is parallel to that of the stop projection *h* hereinafter described.

In the socket *c* a rod *g* having a stop projection *h* slides normally to the shuttle *n*. The outer end of the stop projection is oblique, as shown. Said rod also has a fork *i* which projects thereabove.

This rod is continuously pushed towards the neck by spring *k*.

It will be easily seen that the lever *d* which bears against the wood of the shuttle *n* may undergo two movements by its pivoting about the pin *e* in the slot *b*, one perpendicular to

the axis of the shuttle and the other rotary in the plane of the bracket.

Thus when there is yarn on the tube *l* the rod *g* and the lever *d* occupy the position shown in Figs. 1 and 2 that is to say are moved parallel with the axis of the socket *c* and the axis of the slot *b*.

As the weft is used up the diameter of the tube diminishes and the rod *g* moves upwards more and more under the action of the spring *k* towards the axis of the spindle of the shuttle.

When the minimum quantity of yarn is reached necessitating a change of shuttle, the fork *i* passes around the tube *l* (Fig. 4) and the rod *g* moves to the position shown (Fig. 3). At this moment, the stop *h* moves out of the way and allows the rotary movement of the lever *d* which pushes in the direction of the arrow a rod *m* which operates the shuttle changing mechanism.

This feeler entirely mechanical and operating surely and softly allows for reducing to a minimum the amount of yarn left on the tube.

As will be seen and as follows from the preceding, the invention is not limited to the methods of carrying it out before mentioned nor to its different parts but embraces on the other hand all variations of the rod *g* whether or not ended by a fork *i*.

Having now particularly described and ascertained the nature of my said invention and in what manner the same is to be performed, I declare that what I claim is:

A weft feeler for looms, comprising, in combination with a shuttle and shuttle tube, and with a movable rod for operating shuttle changing mechanism, a supporting element for attachment to the loom frame, having a guide for the said operating rod and also having a slot normal to the shuttle and guides also normal to the shuttle, a feeler rod normal to the shuttle, mounted for movement in said guides and having a fork to engage astride the shuttle tube and also having a stop projection provided with an oblique end, a spring to move the feeler arm toward the tube, a lever having a pivot mounted for movement in the slot of the supporting ele-

ment, said lever being arranged with its free end engageable with the shuttle and also provided with a stop projection having an oblique end slidably engaged with the stop projection of the feeler arm, and a spring active on said lever to cause the same to move said operating rod when the stop projection of said lever is released by that of the feeler rod when the latter moves astride of the tube.

10 In witness whereof I have hereunto set my hand.

GUSTAVE DIEDERICHS.
